VOLTAGE REGULATOR

Ralph H. Preston, Roseland, N. J., assignor to
 American Transformer Company, Newark,
 N. J.

Application October 4, 1944, Serial No. 557,175

11 Claims. (Cl. 171—119)

This invention relates to a voltage regulator of the continuously variable auto-transformer type such as disclosed in Schermerhorn Patent 2,089,434, issued August 10, 1937. The regulator to be described herein is designed particularly for obtaining a variable voltage from a suitable source of alternating current supply and is especially adapted for handling a small current.

One of the objects of my invention is to provide a regulator of relatively low watt capacity which will give exceedingly fine regulation at high efficiency.

A further object of my invention is to provide a construction in which the regulator can be quickly converted from a table mounting to a rear board or panel mounting.

Another object of my invention is to provide a regulator construction in which the contact brush is carried in a new and novel manner whereby a good contact is made between the brush and the arm carrying it, and in which the brush and spring may be very easily removed from the arm for inspection or renewal purposes.

A still further object is to provide improved, simple and cheap means of mounting the transformer core and winding on the base support.

A still further object is to provide improved means for mounting the brush arm and conveying current thereto.

These and other objects will be readily appreciated by one skilled in the art by a reading of the specification taken in connection with the annexed drawings wherein:

Figure 1 is a front elevational view of the complete unit.

Figure 2 is a view on the line 2—2 of Figure 1.

Figure 3 is a part-sectional and part-elevational view, taken on the line 3—3 of Figure 4, and also showing in broken lines the manner in which the regulator can be converted from a table mounting to a panel mounting.

Figure 4 is a view of the bottom of the structure.

Figure 5 is a sectional view on the line 5—5 of Figure 3, all of the views of Figures 1 to 5 inclusive being on a somewhat reduced scale from 45 the operative structure.

Figure 6 is a full-size view of the contact brush spring.

Figure 7 is a diagrammatic view of the electrical circuits of the regulator, including a "Table of 50 connections."

In the various views, wherein like numbers refer to corresponding parts, 6 is a base support of strong and preferably heat-resisting insulating material, such as a thermo-setting, phenolic, rag-filled material, preferably having a plurality of

bosses 7 for resting on a table. The base 6 has a recess 8 from which extends a column 9 preferably moulded integrally with the base 6. The base is provided with a plurality of barriers 10 between 5 which are mounted terminals numbered 1 to 5.

Extending upwardly from the base 6 is an annular flange 11, within the periphery of which is mounted the transformer core 12 and toroidal winding 13, it being understood that the core and winding rest on a cushioning gasket 53.

The core and winding are securely fastened within the periphery of the flange 11 by means of a clamp 14, preferably having some resiliency, having a plurality of arms 15, three of which are utilized as shown in Figure 2. The clamp 14 is held in place on the column, near one end thereof, by a retaining member 16 which is preferably of the locking ring type and is snapped into position in a groove within the column 9. The ends of the arms 15 rest on an annular insulator 17 positioned on the ends 18 of the regulator winding 13.

Positioned within the column 9, is a metallic sleeve or auxiliary shaft 19, on the upper end of which is pressed the hub 20 of the brush arm 21 of suitable metal which may be die-cast aluminum. Preferably the arm 21 and sleeve 19 are assembled as a unit before assembly into the regulator.

It will be noted from Figures 3 and 4, that the sleeve 19 extends within the recess 8 of the base, and positioned over this sleeve is a contact terminal having a circular base portion 22 of suitable material such as copper, and a finger 23 extending outwardly between bosses 49 moulded integrally with the wall of the base recess and connected to the terminal 3.

Engaging the terminal 22, is a spring washer 24 that is held under tension against the terminal 22 by means of a clamping ring 25 held in locking position by a screw and nut 26. The clamp 25 has an integrally formed arm 27 which is adapted to engage a stop 28 moulded integrally with the base 6 to stop the rotation of the brush arm 21 in the position shown in Figure 1. Also fastened to the sleeve 19 and closely adjacent the clamp 25, is a second clamp 29 having an integrally formed arm 30 which is also adapted to engage the stop 28 when the brush arm is moved to its extremity in the other direction from that shown in Figure 1.

Carried within the sleeve 19, is a shaft 31 to which is fastened, as by a pin 32, the sleeve 19, the pin 32 also passing through the hub 20 of the brush arm 21. On the upper end of the shaft 31, is carried a calibration dial 33 and a control knob 34. The free end of the arm 21

is somewhat enlarged and this enlarged portion is provided with a transverse rectangularly shaped hole or orifice 35 within which is positioned a spring 36 for pressing a suitable brush 37 against the contact surface 38 made by removing the insulation from the upper end of the winding 13 so as to expose the conductors which are wound in close relationship. The width of the brush 37 is such that only approximately three of the small conductors are bridged simultaneously, and since the number of conductors in this piece of apparatus is relatively large, a very small change in potential is obtained which may be on the order of $\frac{1}{4}$ to $\frac{1}{2}$ volt.

The brush 37 has fastened thereto a pigtail 39 of fine stranded copper wire which is fastened to the arm 21 by a screw 40 seated in a recess 41 in the arm. It will be noted from Figure 3, that the pigtail 39 is carried up to the screw 40 through a slot 42 which intercepts the orifice 35, into which an opening 43 extends, the width of the opening 43 being in alignment with and approximately the same width as the opening for the brush 37. These two openings extend from opposite sides of the hole 35 through the material of the arm. As a matter of fact, these rectangularly shaped openings are longer than the vertical dimension of the hole 35, thereby forming grooves or channels 54 and 55, within which the brush 37 operates in perfect alignment with the brush track 38.

It will be noted from Figures 5 and 6 that the brush spring 36 is formed in somewhat elliptical shape out of one piece of suitable flat metal such as bronze, spring copper or beryllium copper, and has a recess 44 therein to receive the outer edge of the brush 37, thereby aligning the spring with the brush; while the ends of the spring are formed over and interlocked at 45, and this interlocking formation enters the opening 43 in the end of the arm 21. This provides a very effective and self-aligning means for applying pressure to the brush 37, as well as a simple and quickly operative means for removing the brush for inspection or renewal purposes, for the reason that by a slight pressure on the protruding ends of the spring 36 (see Figure 1), the interlocking formation 45 may be pushed out of the opening 43 when the spring 36 is withdrawn from the orifice 35, and since the width of the opening 43 is slightly more than the thickness of the brush 37, the brush may be withdrawn from its opening through the opening 43 after the binding screw 40 is removed, the pigtail passing through the slot 42.

As shown in Figure 1, the travel of the brush and brush arm is limited as heretofore pointed out by the arms 27 and 30 engaging the stop 28. At the time the arm 27 engages the stop member 28, the brush 37 is limited in its travel up to the edge 48 of an insulating strip 47 positioned over the winding 13. When the arm 30 is in engagement with the stop member 28, on reverse rotation of the arm 21, the brush 37 is then adjacent the edge 46 of the insulating strip 47.

As shown in Figures 1 to 3, the regulator is assembled for mounting on a table and may be fastened thereto through the medium of the mounting holes 50. When it is desired to mount the regulator on the back of a board or panel mounting, all that is necessary to be done is to remove the pin 32 and withdraw the shaft 31, which is provided with a hole 52, shown in dotted lines, at its opposite end, and insert it in reverse

position through the panel 31, shown in broken lines in Figure 3, and then re-insert the pin 32 through the hub 20, the arm 21 and the hole 52, after which the mounting studs may be passed through the panel and through the holes 50 in the base 8. While the shaft 31 may be of suitable metal, I prefer to make it of strong insulating material to absolutely prevent an operator getting an electrical shock, although the handle 34 is of insulating material. Furthermore, if the regulators are arranged in gangs for polyphase use, as shown in Figure 12 of the Schermerhorn patent previously referred to, the shaft of insulating material is necessary.

The methods of making connection to the winding of the regulator and the output voltages are given in Figure 7 and it would appear that further description seems to be unnecessary.

What I claim is:

1. A voltage regulator including a recessed base of suitable insulating material and having an integral centrally located outwardly extending column with a groove therein near its normally free end, a circular core of suitable magnetic material carrying a toroidal winding of closely arranged conductors, the outer turns of which have at least a circularly bared portion to form a brush contact surface, the core and winding being seated at one end on the base around said column, clamping means engaging the opposite end of the winding and core, a retaining member carried by the groove in said column for holding said clamping means in clamping position, a cylindrical metallic sleeve or auxiliary shaft passing through said column, a brush arm securely fastened mechanically and electrically to the cylindrical sleeve at the free end of the column and extending radially from the column and downwardly at its free end over the winding, a brush resiliently carried by the free end of the arm in engagement with said brush contact surface on the winding, an operating shaft passing through said cylindrical sleeve and removably fastened thereto adjacent the free end of the column, a stop within the recess of the base, stop means adjustably carried on the sleeve for engaging said base stop for both directions of rotation of the shaft, and terminals carried by the base for making connections to the winding and sleeve.
2. A voltage regulator including a base of suitable insulating material and having an integral centrally located outwardly extending tapered column with an annular groove near the free end thereof, a core of suitable magnetic material having a winding thereon, the outer turns of which form a cylindrical surface, at least a portion of which is bared to form a brush contact surface, the base having a recess around the foot of said column to receive one end of said core and winding, a resilient clamp for engaging the opposite ends of said core and winding, a retaining member carried by the groove in said column for holding said clamp in clamping position, a hollow auxiliary shaft or sleeve passing through the column at both ends thereof, a brush arm securely fastened to said auxiliary shaft or sleeve at the free end of the column and extending radially from the column, a brush resiliently carried by the free end of the arm for engagement with said brush contact surface on the winding, an operating shaft passing through the auxiliary shaft or sleeve and removably attached thereto, a stop positioned in the base, stop means adjustably carried on the auxiliary shaft or sleeve for engaging said base stop for both directions of

rotation of the shaft, and terminals carried by the base for making connections to the winding and auxiliary shaft or sleeve.

3. A voltage regulator as defined in claim 1, further characterized in that the base is provided with an annular ring, a portion of which is divided by barriers into separate compartments for receiving the terminals for making connections to the winding, electrical connection being made to the auxiliary shaft or sleeve by a terminal fitting over the auxiliary shaft or sleeve against the base of the column, with a spring washer firmly pressed against said member by said stop means carried by the auxiliary shaft or sleeve.

4. A voltage regulator as defined in claim 1, further characterized in that the operating shaft is provided with means near its opposite ends whereby it may be fastened to the auxiliary shaft or sleeve and brush holder when inserted for operation from either end of the regulator, thereby providing for horizontal or vertical mounting.

5. A voltage regulator including a hollow base of suitable insulating material having an upwardly extending annular flange and a centrally located upwardly extending column, a unit core of suitable magnetic material and a winding thereon with a brush track on the winding, the core and winding unit having one end seated within said annular flange, means carried by the column for engaging the opposite end of the core and winding unit to hold the unit securely within the flange, a hollow auxiliary shaft or sleeve passing through the column at both ends thereof, a brush arm securely fastened to said sleeve at the free end of the column and extending radially from the column, a brush resiliently carried by the free end of the arm for engagement with said brush track on the winding, an operating shaft passing through said sleeve and provided with means whereby the operating shaft can be readily connected and disconnected from the sleeve and arm and reversed in position in the sleeve so the regulator may be mounted on a table or on a switchboard or panel, means within the hollow base carried on the said sleeve and cooperating with means on the base for stopping the rotation of the operating shaft and brush arm in both directions of rotation, and terminals carried by the base for making connections to the winding and said sleeve.

6. A voltage regulator as set forth in claim 5, further defined in that the column is tapered upwardly and provided with means for carrying a retaining member for holding said means that engages the core and winding unit to hold the same in place within the flange of the base.

7. In an electrical regulator having a core and winding with a part of the winding bared to form a brush-tracking surface, an operating shaft carrying a brush arm with means for conveying current to said arm, said arm having a transverse hole through its free end with openings at right angles thereto to opposite sides of the arm end, a brush positioned in one of said openings and having contact means with the arm, a spring extending through said hole and having a seat for the brush and a formation extending into the other of said openings for holding the spring in operative position in the arm and against the brush.

8. In an electrical regulator having a core and winding with a part of the winding bared to form a brush-tracking surface, an operating shaft car-

rying a brush arm with means for conveying current to said arm, said arm having a transverse hole through its free end with openings at right angles thereto to opposite sides of the arm end, a brush positioned in one of said openings and having contact means with the arm, a spring formed from a single piece of flat metal into a closed elliptically shaped loop having a seat for the brush on one side of its long axis and an interlocking formation of its ends on the opposite side from the brush seat, the spring being positioned in the transverse hole with the said formation located in the outer of said openings into said hole, while said seat holds the spring in aligning position.

15 9. In an electrical regulator having a core and winding with a part of the winding bared to form a brush-tracking surface, an operating shaft carrying a brush arm with means for conveying current to said arm, said arm having a transverse hole through its free end with openings at right angles thereto to opposite sides of the arm end, a brush positioned in one of said openings and having contact means with the arm, a spring formed from a single piece of flat metal into a closed elliptically shaped loop having a seat for the brush on one side of its long axis and an interlocking formation of its ends on the opposite side from the brush seat, the spring being positioned in the transverse hole with the said formation located in the outer of said openings into said hole, while said seat holds the spring in aligning position.

20 25 30 35

10. In an electrical regulator having a core and winding with a part of the winding bared to form a brush-tracking surface, an operating shaft carrying a brush arm with means for conveying current to said arm, said arm having a transverse hole through its free end with openings at right angles thereto to opposite sides of the arm end, a brush positioned in one of said openings and having contact means with the arm, a spring formed from a single piece of flat metal into a closed elliptically shaped loop having a seat for the brush on one side of its long axis and an interlocking formation of its ends on the opposite side from the brush seat, the spring being positioned in the transverse hole with the said formation located in the outer of said openings into said hole, while said seat holds the spring in aligning position, the ends of the spring loop projecting beyond the edges of the arm end whereby pressure on these loop ends will force said formation on the spring out of its position in its arm opening so the spring may be readily withdrawn from the hole in the arm.

40 45 50

10. In an electrical regulator having a core and winding with a part of the winding bared to form a brush-tracking surface, an operating shaft carrying a brush arm with means for conveying current to said arm, said arm having a transverse hole through its free end with openings at right angles thereto to opposite sides of the arm end, a brush positioned in one of said openings and having contact means with the arm, a spring formed from a single piece of flat metal into a closed elliptically shaped loop having a seat for the brush on one side of its long axis and an interlocking formation of its ends on the opposite side from the brush seat, the spring being positioned in the transverse hole with the said formation located in the outer of said openings into said hole, while said seat holds the spring in aligning position, the ends of the spring loop projecting beyond the edges of the arm end whereby pressure on these loop ends will force said formation on the spring out of its position in its arm opening so the spring may be readily withdrawn from the hole in the arm, the arm end having a recess for a binding and contact screw above the location of the brush, with a slot extending downwardly from the recess into the opening for the said spring formation and transverse hole to form a passageway for a pigtail from the brush to the recess and screw therein, the last-mentioned opening having a width so the brush may be withdrawn therethrough after the spring is removed.

70 75 11. An electrical regulator as defined in claim 10, further characterized in that said openings are rectangular in shape and extend in the material of the arm beyond the vertical dimension of the spring hole, thereby forming grooves to function with the brush.

RALPH H. PRESTON.
